FERDINAND BADER, OF HAMBURG, GERMANY

SOUND RECORD RECEPTACLE

Application filed February 16, 1932, Serial No. 593,247, and in Germany May 29, 1931.

For the storing of sound records in boxes and similar receptacles, so that they can be easily observed, it is already known, to place semi-circular supports of U-shaped cross section oscillatable on a common axle, a rod or the like. These semi-circular supports were hitherto oscillatably mounted at one end only. The other end was not guided. Consequently, there is a certain amount of play between 10 two record supports, so that one support can scrape against the record in another support during removal.

In order to avoid this objection in a record receptacle with semi-circular record supports oscillatably mounted at one end, record supports are provided according to the invention each with a downwardly extending rib-like projection, which is guided in a slot in the bearing plate on the entire length of 20 the path of oscillation. Consequently, this invention absolutely avoids damaging of the records when being inserted in the supports. Moreover by lifting the supports when removing the records no damage of the records 25 can be caused.

An embodiment of the invention is illustrated by way of example in the accompanying drawing in which:

Fig. 1 shows the receptacle in perspective view, one side wall removed.

Fig. 2 is a side view of a record support.

Fig. 3 shows in top plan view the arrangement of the record supports in the bearing plate.

Fig. 4 shows in side elevation an insert for small records.

In a box *b* having a hinged lid *a* several supports *c* of aluminium, hard rubber, celluloid, papier-mâché or the like for records are mounted at their rear end on an axle *d* so that they can oscillate around this axle. The supports *c* are guided at their front end in slots *e* of a bearing plate *f*. For this purpose the record supports *c* have, according to the invention, on the outer side (Fig. 2) a rib-like extension *n*, which is reliably guided in the slots *e* during the entire oscillation of the record support *c*. Each record support *c* has at this side at the upper end a shoulder *g* 50 for the insertion of a hook key *h*. The in-

dividual record supports *c* can be lifted and turned around the axle *d* by means of this key *h*, as shown in Fig. 1. The removal of the records *i* is thereby facilitated. The key has an eye *o* for inserting a finger. 55

Each record support *c* is composed of three parts, namely two outer plates *c₁*, *c₂* and an inner plate *c₃* (Fig. 3) enclosed between the outer plates. The upper edge of the inner plate *c₃* is lower than the upper edge of the outer plates *c₁*, *c₂* so that a groove is formed serving for accommodating the record, which is introduced from above into the semicircular record support *c*. 60

For facilitating the selection of a record 65 a graduation *m* may be arranged on the top side of the bearing plate *f*. Each record receptacle may be arranged for records of one and the same size or for records of all sizes. For records smaller than the commonly used records inserts *l* may be used which have a groove in the upper edge designed to hold the small record. 70

I claim:—

1. A receptacle for sound records, comprising in combination a box, an axle fixed in said box, a bearing plate having slots in its inner edge fixed in said box at a distance from said axle, semicircular record supports having a groove in the upper edge each 75 adapted to carry a record oscillatably mounted at the rear end on said axle, and a downwardly extending rib-like projection on the front end of each support adapted to engage with the corresponding slot in said bearing 80 plate and to reliably guide said support during the entire oscillating movement of the same. 85

2. A sound record receptacle as specified in claim 1, comprising in combination with 90 the record supports, an insert plate having a groove in the upper edge corresponding to the circumference of small records adapted to be inserted in said supports for accommodating small records. 95

In testimony whereof I affix my signature.
Dr. FERDINAND BADER.
